UNITED STATES PATENT OFFICE.

DANIEL S. BROWN, OF BURDETTE, NEW YORK.

PIPE-WRENCH.

SPECIFICATION forming part of Letters Patent No. 293,848, dated February 19, 1884.

Application filed January 8, 1884. (Model.)

To all whom it may concern:

Be it known that I, DANIEL S. BROWN, of Burdette, in the county of Schuyler and State of New York, have invented a new and Improved Pipe-Wrench, of which the following is a full, clear, and exact description.

Reference is to be had to the accompanying drawings, forming a part of this specification, in which similar letters of reference indicate corresponding parts in both the figures.

Figure 1 is a sectional side elevation of my new and improved pipe-wrench, and Fig. 2 is a front elevation of the same.

The invention will first be described in connection with the drawings, and then pointed out in the claim.

A represents the main body of the wrench; B, the handle, and C the movable jaw of the wrench. The main body A is chambered or slotted, as shown at a , and is formed at its outer end with the fixed jaw a' , which is slightly curved backward toward the handle portion a^2 of the main body A. The handle B is pivoted in the slot or recess a of the main body A upon the pin b , and the handle is formed at its forward end with the toothed sector b' , which intergears with the toothed sector c' , formed upon the rear end of the jaw C, the jaw being pivoted in the said recess a of the main body A upon a pin, c , as shown in Fig. 1. The jaw C, besides being formed with the toothed sector c' , is curved and formed upon its outer convex edge with the teeth c^2 , and

these teeth are cut diagonally across the edge of the jaw, as shown in Fig. 2, so that the jaw, when brought down upon a pipe by the handle B, will present sharp teeth to the surface of the pipe in the wrench, and effect a firm and secure hold upon the pipe, so that it may be turned by the wrench.

By gearing the handle B and jaw C together by the sectors $b' c'$, it will be seen that by raising the handle B to the position shown in dotted lines in Fig. 1, the jaw C will be opened—that is, brought to the position shown in dotted lines—so that the wrench may be easily applied to a pipe or other object to be turned, and by bringing the handle B down toward the handle portion a^2 of the main part A, the jaw C will be closed upon and held with great firmness upon the pipe or other object to be turned.

Having thus fully described my invention, I claim as new and desire to secure by Letters Patent—

The pipe-wrench herein shown and described, consisting of the main body A, formed with the recess a , jaw a' , and handle portion a^2 , and of the handle B and jaw C, pivoted in the recess a , the handle and jaw being geared together by the sectors $b' c'$, substantially as and for the purposes set forth.

DANIEL S. BROWN.
